UNITED STATES PATENT OFFICE.

FRANK L. WRIGHT, OF CHICAGO, ILLINOIS, ASSIGNOR TO THE LUXFER
PRISM PATENTS COMPANY, OF SAME PLACE.

DESIGN FOR A PRISM-PLATE.

SPECIFICATION forming part of Design No. 28,012, dated December 7, 1897.

Application filed October 23, 1897. Serial No. 656,237. Term of patent 14 years.

To all whom it may concern:

Be it known that I, FRANK L. WRIGHT, a citizen of the United States, residing at Chicago, in the county of Cook and State of Illinois, have invented a certain new and original 5 Design for Prism-Plates, of which the following is a description.

My invention relates to designs for prism-plates and is illustrated in the accompanying 10 drawings.

Figure 1 is a plan view of a prism-plate embodying my design. Fig. 2 is a cross-section.

A is the body of the prism-plate; B B, a series of surface areas formed by the lines of 15 separation C C. D D are a series of prisms on the other side of the plate, and E E prisms on some of the surface areas scattered about over the surface. When viewed from the prism side, there is a uniform prism-surface.

When viewed from the other side, there is a 20 series of surface areas some of which are provided with prisms and others forming a "field," so to speak.

The essential features of my design are found in a prism-plate comprising a substantially flat extended body with a series of prisms on one side and on the other a series of lines of separation which divide the surface into a number of surface areas, and prisms on various of such surface areas. 25 30

I claim—

A design for a prism-plate, substantially as shown and described.

FRANK L. WRIGHT.
